UNITED STATES PATENT OFFICE

148,286

DESIGN FOR A CHAIR

Roy A. Cramer, Kansas City, Mo.

Application September 27, 1946, Serial No. 133,607

Term of patent 14 years

(Cl. D15—1)

To all whom it may concern:

Be it known that I, Roy A. Cramer, a citizen of the United States, residing at Kansas City, in the county of Jackson and State of Missouri, have invented a new, original, and ornamental Design for Chair, of which the following is a specification, reference being had to the accompanying drawings, forming part thereof.

In the drawings illustrating my new design:

Fig. 1 is a side view of a chair showing my new chair design, and

Fig. 2 is a front perspective view of the chair of Fig. 1.

The characteristic features of the new design reside in the portions shown in solid lines.

I claim:

The ornamental design for a chair, substantially as shown and described.

ROY A. CRAMER.
